UNITED STATES PATENT OFFICE.

EDWIN R. GILL, OF YONKERS, NEW YORK.

PULP-COLLECTING FORM.

1,161,125.

Specification of Letters Patent. Patented Nov. 23, 1915.

Application filed January 29, 1915. Serial No. 5,010.

To all whom it may concern:

Be it known that I, EDWIN R. GILL, a citizen of the United States, residing at Yonkers, in the county of Westchester and State 5 of New York, have invented certain new and useful Improvements in Pulp-Collecting Forms; and I do hereby declare the following to be a full, clear, and exact description of the invention, such as will enable 10 others skilled in the art to which it appertains to make and use the same.

The present invention relates to means whereby the forms employed in paper manufacture for collecting pulp by suction, or 15 for transferring more or less finished material by air pressure may be perfected. Forms of this character are generally made with wire gauze surfaces, behind which are chambers into which air and water may be 20 drawn, leaving a layer of pulp upon the perforated gathering surface. In constructing various shapes in this manner it is frequently difficult or impossible so to join the sheets of gauze on the surfaces as to secure 25 a substantially uniform deposit, owing to the necessity of using solder, etc., for fastening joints, as well as to use in many cases of imperforate reinforcing material. It is this difficulty which my present invention is 30 designed to remove.

I have discovered that fibrous material having a capillary action can be employed so as to exert its influence as a group of finely divided ducts along its mass, as distinguished from merely using it for direct 35 transmission of pressure through the same. By so using the fibrous material, I am able to extend the scope or sphere of influence of the suction exerted through the perforate 40 material, as wire gauze, to imperforate areas near it, such as result from the imperfections at joints above mentioned.

My invention is illustrated in the accompanying drawings in a form serving as a 45 mere example.

Figure 1 shows in diagram an apparatus for using a cylindrical former of the class above mentioned and in Fig. 2 the said former is shown partly in elevation and 50 partly in section, supplied with my invention.

The gauze covered collecting form is shown at 10 in Fig. 1, and its suction chamber is connected by a pipe 11 with the bottom of a reservoir 12, from which air is exhausted by a pump 13 connected to said reservoir by a pipe 14 and driven by a belt 15.

The details of the hollow form 10 are shown in Fig. 2, this form being designed to 60 resist material pressures for compacting the layer of pulp. For this purpose it comprises an interior shell 16 made of sheet metal provided with many perforations distributed with substantial uniformity. Over 65 the cylindrical surface of this shell is fitted the covering of wire gauze 17 and a similar gauze covering 18 is fitted over the flat end of the form.

In order safely and securely to join the 70 flat sheet 18 to the cylindrical sheet 17, the two are overlapped as shown, and jointed by solder or brazing as indicated at 19. The two thicknesses of gauze would in itself introduce an element of disturbance and would 75 prevent uniform action and the presence of solder increases this present disadvantage.

I remedy this difficulty as follows: The 80 two sheets of gauze are bent over as shown to form a channel for the area of disturbance. Within this channel is fitted a strip of felt or other suitable capillary substance 85 which is fastened in place in any suitable manner, as for instance, by sewing. The stitching is indicated in dotted lines. The operation of the capillary body 20 is to 90 absorb the water which is carried off longitudinally or along the surface toward those parts of the gauze covering which best transmit the air pressure. I have found that where a capillary body is employed in this 95 manner to extend the influence of the sucking action transmitted through the gauze, a substantial uniform effect is secured over the entire form, thus obviating the difficulties otherwise due to the joints.

What I claim is—

1. In a pulp-collecting form having the usual perforate material and having joints offering material obstruction to passage of 100 air, a layer of capillary material fastened as a covering over said joints, whereby the

scope of atmospheric action is extended along said material to produce a substantially uniform surface action.

2. In a pulp-collecting form, two layers of wire gauze, overlapping to form a channel, means for fastening the same to form a joint at the overlapping points, and capillary material laid in said channel and fas-

tened therein, for the purpose substantially as described. 10

In testimony whereof, I affix my signature, in presence of two witnesses.

EDWIN R. GILL.
